Jesse Blackinton.

United States Patent Office

JESSE BLACKINTON, OF ROSCOE, ILLINOIS.

Letters Patent No. 69,962, dated October 22, 1867.

IMPROVED BOLT-TRIMMER.

The Schedule referred to in these Letters Patent and making part of the same.

Be it known that I, JESSE BLACKINTON, of Roscoe, in the county of Winnebago, and State of Illinois, have invented a new and useful Bolt-Trimmer, or implement for trimming or cutting bolts, rivets, &c.; and I do hereby declare that the following is a full, clear, and exact description of the construction and operation of the same, reference being had to the annexed drawings, making a part of this specification, in which—

Figure 1 is a perspective view.

Figure 2, a view of one of the levers.

Figure 3, of one of the cutters, and

Figure 4, of a connection of one of the cutters.

Like letters in the different figures refer to like parts.

The nature of my invention consists in so hinging or connecting the cutters A A in my bolt-trimmer to the levers L and M, that the cutting edges C C will not only be parallel with each other when closed, but also parallel, or nearly so, when opened, so that when they are opened a bolt or rivet to be trimmed may be inserted with equal facility at all points between the cutting edges, whether near to the fulcrum or remote therefrom; and also so that the edges of the cutters, when engaging with and passing through the metal to be divided, will maintain a parallel relation to each other, instead of opening widest at the points most remote from the fulcrum, as is the case with other bolt-trimmers and cutters.

My invention also comprises a new way of connecting and compounding the lever D with the shorter lever M and the lever L, so as to increase the strength of the connection; also a set-screw, arranged so as to prevent the cutting edges C C from being injured; also a slot and bearing-pin, by which the lever D operates the lever M; also a flat-headed bolt, working in a slot, to insure the proper approach of the cutting edges.

To enable others skilled in the art to make and use my invention, I will proceed to describe its construction and operation.

I prefer to make the principal levers of malleable iron, on account of cheapness, but they may be made of any other suitable material. The cutters A A are made of steel. The connections B B may be made either of steel or iron. The cutters A A are made to vibrate on the bolts which attach them to the levers or jaws L and M, so that, as they are opened and closed, the connections B B, operating on the ends of the cutters A A, will move them so as to maintain the parallelism of their cutting edges C C. By changing the relative lengths of the cutter-arms A A and the connections B B, the cutting edges C C may be made to open most at the outer points or the inner points, as desired. For instance, if the arms A A are made of shorter proportion than that represented in the drawings, the cutting edges will open wider at their inner points, and if lengthened, they will open wider at their outer points.

That part of the lever L represented at the point H is provided with a recess in its under side, to receive an elevated bearing, H', on the end of the lever D. This gives greater strength to the connection, in proportion to the expenses and convenience of manufacture, than would otherwise be the case.

I also make a set-screw, I, which stops the action of the levers, by contact with the stop O, so as to prevent the cutting edges C C from being injured by each other. In the lever D, I make a slot, F, in which operates the pin E, for moving the shorter lever M, to which the pin E is attached. I also make a flat-headed bolt, P, which is fastened to the lever M, and works in the slot R, bearing on the lever L, to keep their inner surfaces together and insure a direct approach of the cutting edges C C.

What I claim as my invention, and desire to secure by Letters Patent, is—

1. The combination and arrangement of the cutters A A with the connections B B and the levers L M, as herein described, for the purposes set forth.
2. The arrangement of the recess H and the elevated bearing H', in combination with the levers D, L, and M, for the purposes set forth.
3. The slot F and the pin E, in combination with the levers D, L, and M, when arranged as and operating for the purposes set forth.
4. The flat-headed bolt P, in combination with the slot R and the levers L and M, when arranged as and operating for the purposes set forth.

JESSE BLACKINTON.
